UNITED STATES PATENT OFFICE.

MAX KRAUSS, OF PHILADELPHIA, PENNSYLVANIA.

TALKING-MACHINE.

1,291,027.

Specification of Letters Patent. Patented Jan. 14, 1919.

Application filed June 29, 1918. Serial No. 242,549.

To all whom it may concern:

Be it known that I, MAX KRAUSS, a subject of the King of Bavaria, having resided in the United States one year last past and having declared my intention of becoming a citizen thereof, residing in the city and county of Philadelphia, State of Pennsylvania, have invented a new and useful Talking-Machine, of which the following is a specification.

My invention relates to the general class of talking or sound-reproducing machines which play records in the form of flat disks, and has for its primary object the construction of a machine in which a plurality of records, either single or double-faced, and of any desired diameter, can be set up, and any one of them, at the selection of the operator, be played.

My invention embodies improvements upon a talking machine invented by and patented to me under United States Letters Patent, No. 1,199,192, dated September 26, 1916, and its object is to enable me to remove any one of the disks without as in the construction of my patent being under the necessity of removing a given number or assemblage of them.

In other particulars this invention is characterized by the general features and advantages of my patented machine in that it is a mere matter of dimensions as to what number or diameter or character of disk records it can play.

My present machine, moreover, is adapted for use with any form of sound box, the stylus of which can operate upon either the up-and-down tone groove of the type of the "Edison" or the in-and-out tone groove of the type of the "Victor" machines, only one sound box being necessary to enable the operator to at will select and play any one of any desired number of records which happen to be set up in the machine.

The machine, moreover, is capable of being operated by any preferred type of motor, mechanical or electrical.

With these primary ends in view and for the purpose of the construction of an inexpensive, mechanically simple and durable machine, I have resorted to a construction which I have hereinafter explained, for the purpose of simplifying the description, having shown a machine adapted to operate with a double group or series of five records each, all in vertical disposition, although of

course the group may be disposed horizontally, the entire cabinet and motive mechanism being correspondingly reversely disposed.

As already stated, moreover, it is a mere matter of the proportioning of the machine and the duplication of certain parts hereinafter described, to adapt the machine to play a much larger number of records than five.

In the accompanying drawings I have, for the purpose of illustrating my invention, shown a certain type and embodiment of it which is at present preferred by me, because in practice it has given satisfactory and reliable results.

It is to be understood, however, that the various instrumentalities in which my invention is embodied can be variously arranged and organized and that my invention is not therefore limited to the precise arrangement and organization of such instrumentalities as are typified in the construction illustrated in the accompanying drawings and herein described.

In the accompanying drawings:

Figure 1 represents in top plan so much of a talking machine embodying my invention as is necessary to illustrate it.

Fig. 2 represents in side sectional elevation on the dotted line 2-2 of Fig. 1, the machine of Fig. 1, certain of its component instrumentalities being shown in side elevation.

Fig. 3 is a fragmentary side view upon an enlarged scale, of one group of records partly in section and partly in elevation, the sight being taken on the dotted line 3-3 of Fig. 1.

Fig. 4 is a fragmentary end elevation on the line 4-4 of Fig. 2; and

Fig. 5 is a fragmentary side view of a modification.

Similar numerals of reference indicate corresponding parts.

Referring to the drawings:

1 designates a vertically standing casing or cabinet of any preferred character, material and dimensions, which by means of a partition 2, shown as horizontally disposed, is divided into two hollow interior compartments, the upper of which I designate 3 and the lower 4.

Within the upper compartment are located the groups of separately removable disks or records each of which is designated by the number 5 and which in the construc-

tion shown are composed of two disks, presumably one-faced disks, spaced side by side with their sound grooves upon their respective outsides.

5 In order to support the groups and at the same time render the records removable, I make the shaft upon which they are mounted and from which they are removable in separate parts, and referring now 10 to Fig. 3, I have designated the separated parts or sections of the shaft as 6^1 , 6^2 , 6^3 and 6^4 , which as will be apparent are mounted in separated boxings or bearings 15 7^1 , 7^2 , 7^3 and 7^4 respectively mounted upon standards 8^1 , 8^2 , 8^3 , 8^4 erected from the partition 2 of the casing.

This partition 2 is formed with a central circular aperture 9 and over this aperture, concentrically with respect to its center, is 20 mounted the disk-carrying plate 10 which itself is circular and of slightly greater diameter than the aperture in the partition, over and with respect to which it is mounted and rests free to be rotated or turned by 25 having its outer edge overlap and rest upon a circular track 11 on the partition, with respect to which it, said plate, and the standards, bearings and shafts, and records which it carries, are adapted to be turned 30 so as to completely transpose the positions of the disks relatively to the soundbox, not shown.

The shaft as an entirety, that is to say, the divided parts of it, indicated, as explained, by the numbers 6^1 to 6^4 ,—is mounted upon two shaft supports 12, 13, fastened to and springing from the disk carrying plate 10 near the ends of a selected diameter of said plate, and is mounted for rotation 40 in bearings 14, 15, on said supports.

The disk carrying plate 10 is formed with a series of parallel slots 16, Figs. 1 and 3, through which the records and the record clamping disks 17 and 17^* pass so that segments of the records pass down into the lower compartment and counterpart segments pass up into the upper compartment of the casing.

The disk carrying plate as an entirety is 50 supported so as to rest flat upon the circular track 11 by a central pivot or stem 18 itself springing vertically from a bracket 19 bolted at 20 within the lower compartment of the casing.

55 The pivot or stem 18 is bolted at 21 to the outer end of the bracket 19 and the connection of the plate 10 with the pivot 18 is preferably by means of a sleeve 22 connected at its upper end with the plate 60 and forming in a sense a rotary bearing upon the pivot.

In the normal position of the mounting of the records, one of the outer ends of the shaft as an entirety,—each of which 65 ends is provided with a notch 23 (and 24),—

is connected with a notched pin 25 on the end of a supplemental or driving shaft 26 mounted in a bearing 27 erected on a standard 28 springing from the partition 2. The end of the driving shaft beyond the notched end is equipped with a toothed spur wheel 29, which passes downward through a slot 30 in the partition 2 into the lower compartment 4 of the casing, and is therein adapted to be engaged with and operated by a pinion, 75 not shown, but supposedly connected with any suitable motor, also not shown.

The periphery of the disk carrying plate 10 is provided with two notches 31, 32, diametrically opposite to each other, and either of which is adapted to be engaged by a locking plate 33, provided with a thumb screw 34, on the partition 2 in such position radially toward the circular plate 10 as to be adapted to engage within either one of said notches 31 and 32 and thereby hold the shaft as an entirety of the plate in alignment with the driving shaft 26,—whether said shaft be in the position shown in Figs. 1 and 2,—or in the precisely reverse position, not of course shown, which it would assume when the plate and all of its adjuncts are lifted so as to disengage the notch at an end of the shaft from the driving shaft and permit of the complete turning 95 around of the plate and records to present the opposite sides of said records to the stylus of the soundbox.

In order conveniently to apply and remove any one of the records from the shaft, 100 considered as an entirety, I make use of the following as the contrivance for that purpose:

17, 17^* are respectively a pair of clamping disks preferably of the form shown particularly in Figs. 3 and 5, that is to say, internally or as to their respective opposing faces slightly concave and as to their separated or outside faces slightly convex.

In the construction typically illustrated, 110 the left-hand clamping disk 17 is fixedly mounted, so as not to be slideable, upon the right-hand end of a given shaft section 6^1 , 6^2 , 6^3 or 6^4 , and is a jam fit against a collar 115 6^* on said section,—the collar bearing against a side of one of the group of bearings 7^1 , 7^2 , 7^3 and 7^4 . Obviously, these left-hand clamping disks in the assemblage of the parts rotate fixedly with the sections of the shaft.

120 Each section of the shaft, taking for example, section 6^3 of Fig. 3, is internally longitudinally bored at 6^6 to a sufficient distance to permit it to receive a coiled spring 35, which is inserted between the inner end 125 of a bore and a locking pin 36, which passes through slots 37 radially opposite each other and longitudinally extending a certain distance through the shaft section, in the present instance 6^3 , and passes also 130

through a hub 17² formed upon the clamping disk 17^x.

From this construction, it will be apparent that in order to apply a record to a given pair of clamping disks and so to the shaft, the slidably movable disk 17^x is adapted to be moved to the right, as shown to the right-hand side of Fig. 3, with the result through the action of the pin 36 of compressing the spring 35. The disk 17^x will then have moved a sufficient distance to the right to permit of the moving of the record likewise to the right and off the right-hand end 6³ of the shaft section to permit of the clearance of the record and its taking out of the machine.

In other words, the central record shown in Fig. 3 is clamped between the disks 17 and 17^x when said disks are brought together by the left-hand movement of the disk 17^x, the spring 35 holding said disk in its then clamping position,—whereas in the view to the right of said Fig. 3, the clamping disks have been separated, the spring compressed, and the record cleared so as to be removable.

This in and out movement of one of the clamping disks is intended to be accomplished by hand by for instance taking hold of the pin 36 and moving it to the right to compress the spring and let the record be free, or permitting it to be moved to the left to clamp the record against the other disk 17 when the central hole in the record has been slipped over the end of the shaft section 6³, as shown with respect to the central record of said Fig. 3. Obviously, either one of the clamping disks may be provided with a spring, and obviously also, if desired, the spring instead of being entered within a bore in the shaft section, may be mounted so as to surround an extension 8^x of, for instance, a standard 8³, as shown in Fig. 5.

38 are a pair of lugs or other projections either separately applied or in the form of a transverse pin, which are mounted upon the hubs 17² or 8^x in the construction of Fig. 5, which when the clamping disks are so closely assembled that it is hard to reach them with 50 the fingers, make it possible to effect the movement of the movable clamping disk by the use for instance of a spanner.

Having now described a convenient construction typically embodying my invention, it will be understood that in its use I am not limited to any particular number or any diametric size of record, as either the usual ten or twelve inch sizes may be used.

It will be further understood that while the construction described enables me with ease to apply and remove the desired number of records, the entire groups can be easily reversed by the reversal of the disk carrying plate without the independent removal of any one of the records,—that is

to say, after I have assembled the records which I desire to use in for instance the two groups represented, I can, by the turning of the disk carrying plate, reverse both groups together, or, if I desire to reverse only one of the groups, lift its shaft up and reverse that group without the reversal of the carrying plate. In other words, I can effect the complete reversal without lifting out the shafts or effecting the reversal of either or any plurality of groups without the removal of the shafts, by the rotation of the carrying plate,—the shafts remaining in place.

Having thus described my invention what I claim as new and desire to secure by Letters Patent, is:—

1. A sound reproducing machine of the character stated, which comprises in combination:—a casing divided into an upper and a lower compartment separated by a partition formed with a central circular aperture,—a circular record-carrying plate axially coincident with the center of the aperture, mounted so as to be rotatable with respect to said aperture and provided with a series of parallel slots,—a plurality of groups of revoluble records disposed in adjacent parallel planes upon a shaft composed of separate but alined and connectible sections which as an entirety supports the entire group of records,—a shaft composed of separate but alined and connectible sections mounted upon said record carrying plate,—and means for attaching and removing the records of each group independently of each other to and from the sections of the shaft.

2. A sound reproducing machine of the character stated, which comprises in combination:—a casing divided into an upper and a lower compartment separated by a partition formed with a central circular aperture,—a circular record-carrying plate axially coincident with the center of the aperture, mounted so as to be rotatable with respect to said aperture and provided with a series of parallel slots,—means for retaining the record carrying plate in fixed position with respect to the central circular aperture,—a plurality of groups of revoluble records disposed in adjacent parallel planes upon a shaft composed of separate but alined and connectible sections which as an entirety supports the entire group of records,—a shaft composed of separate but alined and connectible sections mounted upon said record-carrying plate,—and means for attaching and removing the records of each group independently of each other to and from the sections of the shaft.

3. A sound reproducing machine of the character stated, which comprises in combination:—a casing divided into an upper and a lower compartment separated by a partition formed with a central circular

- aperture,—a circular record-carrying plate axially coincident with the center of the aperture, mounted so as to be rotatable with respect to said aperture and provided with 5 a series of parallel slots,—a plurality of groups of revoluble records disposed in adjacent parallel planes upon a shaft composed of separate but alined and connectible sections which as an entirety supports the entire group of records,—a shaft composed of 10 separate but alined and connectible sections mounted upon said record-carrying plate,—and means for attaching and removing the records of each group independently of each 15 other to and from the sections of the shaft, which comprises a plurality of revoluble record-clamping disks and a corresponding plurality of spring-controlled movable revoluble record-clamping disks, mounted upon the sections 20 of the shaft.
4. A sound reproducing machine of the character stated, which comprises in combination:—a casing divided into an upper and a lower compartment separated by a 25 partition formed with a central circular aperture,—a circular record-carrying plate axially coincident with the center of the
- aperture, mounted so as to be rotatable with respect to said aperture and provided with a series of parallel slots,—means for retaining 30 the record-carrying plate in fixed position with respect to the central circular aperture,—a plurality of groups of revoluble records disposed in adjacent parallel planes upon a shaft composed of separate but alined 35 and connectible sections which as an entirety supports the entire group of records,—a shaft composed of separate but alined and connectible sections mounted upon said record-carrying plate,—and means for at- 40 taching and removing the records of each group independently of each other to and from the sections of the shaft, which comprises a plurality of revoluble record-clamping disks and a corresponding plurality of 45 spring-controlled movable revoluble record-clamping disks, mounted upon the sections of the shaft.

In testimony whereof I have hereunto signed my name this 27th day of June, 1918. 50

MAX KRAUSS.

In the presence of:—

J. BONSALL TAYLOR,
C. D. McVAY.
